UNITED STATES PATENT OFFICE.

OTTO J. GROEHN AND WILLIAM BLASKEWITZ, OF DETROIT, MICHIGAN, ASSIGNORS
TO CLAYTON & LAMBERT MANUFACTURING COMPANY, OF DETROIT, MICHIGAN, A
CORPORATION OF MICHIGAN.

FIRE-POT CONSTRUCTION.

Application filed January 5, 1925. Serial No. 661.

The invention relates to fire pots and refers more particularly to fire pot constructions such as are adapted for plumbers' use or where other uses for oil burning devices of this character are desired.

One of the objects of the invention is to provide a fire pot construction which is provided with a short direct fuel feed to the burner. A further object is to provide means for efficiently heating the fuel during its passage to the burner. Another novel feature resides in the provision of an efficient burner arrangement. Other objects include a fire pot construction which may be readily assembled; also a burner construction employing a single valve.

With these and other objects in view, the invention resides in the novel features of construction and combination and arrangements of parts as more fully hereinafter described and claimed.

Referring to the drawings:

Figure 1 is a vertical elevation partly in section,

Figure 2 is a plan with the hearth rest and the upper part of the combustion chamber removed;

Figure 3 is a perspective view showing the flame plate, and

Figure 4 is a plan view of the fire pot.

In the drawings reference character 10 indicates the tank of a fire pot having the usual filler 10', pump 11, and supporting standards 12 which carry the combustion chamber, the latter comprising lower and upper parts 13 and 14 respectively. The lower part 13 preferably has a threaded engagement with the standards 12, the standards at their other ends being bolted to the spider 15 rigidly mounted on the tank

10. The upper part of the combustion chamber 14 may be bolted to the lower part 13, a hearth rest 16 being located between the combustion chamber parts. The hearth rest is provided with a forward extension formed with openings 17 adapted to receive a suitable bracket (not shown) for supporting soldering irons and other tools.

Fuel in the nature of a hydrocarbon, such as gasoline, etc., is supplied upwardly from tank 10 through the feed pipe 18 which passes through the intake manifold 19, preferably at the point where the manifold divides forming the oppositely extending con-

duits 21, each of which terminates in a burner 22. Each burner is provided with a longitudinal slot 23 directed inwardly toward the combustion chamber. Within the combustion chamber is positioned the flame plate 24 having a curved part 25 adapted to fit around the manifold 19 and the laterally extending portions 26 cooperating with the slots 23 to deflect the flame therefrom toward the center and thence upwardly of the fire pot combustion chamber.

The fuel after passing through the vertical feed pipe 18 and manifold 19 passes above one of the conduits such as the conduit 21, through pipes 27 and 28, the latter pipe preferably containing a wire stuffing 29 whereby the gas passing through pipe 28 is uniformly distributed therein and consequently heated uniformly. From the pipe 28 the gas passes by way of conduit 30 to the valve chamber 31 whence its passage into the intake manifold 19 is regulated by a needle valve 32 operable by a handle 33. The end of the manifold 19 adjacent the valve chamber is preferably open so that air is entrained at 34 with the incoming fuel and conducted therewith through the manifold 19 to the burners 22. Pivoted to the valve chamber as at 35, is a lighter member 36 operable by a handle 37 and having a deflector portion 38 curved so as to deflect the gas rearwardly of the valve chamber as it escapes therefrom.

The lighter 36 permits convenient means for initially lighting the fire and by reason of the curved portion 38 the gas is rearwardly directed in a concentrated jet which may be lighted. After the burners 22 are lighted the lighter 36 is swung on its pivot 35 to one side.

If desired, a heat shield 39 may be provided between the tank 10 and the fire chamber to protect the tank from heat from the fire chamber.

From the foregoing it will be readily seen that we have provided a short direct feed for the fuel, passing through the intake manifold where it is preheated and then passing above one of the burners. In order to more positively heat the fuel as it passes over the burner through pipe 28, the burner may be provided with openings 40 along the upper part, which will cause a flame to impinge upon the pipe 28. By this construction and

the provision of the wire stuffing 29, the intake gas is thoroughly and uniformly heated, both the gas and the mixture passing through the combustion chamber before ignition. We 5 also have provided a construction which employs only a single valve for controlling the supply of fuel, together with an improved means for initially lighting the burners. Other novel features include the provision 10 of a construction which is compact and readily assembled.

While it is believed that from the foregoing description, the nature and advantage 15 of our invention will be readily understood, we desire to have it understood that we do not limit ourselves to what is herein shown and described and that such changes may be resorted to when desired as fall within the scope of the claims.

20 What we claim as our invention is:—

1. In a fire pot construction, a combustion chamber, a pair of opposed burners within said chamber, an intake manifold lying between said burners, a flame plate overlying 25 the manifold and arranged to direct the flame from said burners inwardly of the combustion chamber, a source of fuel, and means for supplying said manifold with the fuel.

30 2. In a fire pot construction, a combustion chamber, a pair of opposed burners within said chamber, an intake manifold lying between said burners, a flame plate overlying the manifold and arranged to direct the flame from said burners inwardly of the combustion chamber, a source of fuel, and means for supplying said manifold with the fuel, said means including a conduit for subjecting the fuel to the heat of the combustion 35 chamber prior to its admission into said manifold.

3. In a fire pot construction, the combination with a fuel tank, of a combustion chamber supported above the fuel tank, an intake 45 manifold extending transversely of the combustion chamber, a plurality of burners communicating with the manifold and lying at opposite sides thereof, said manifold and burners lying in a common plane, and a fuel feed pipe extending upwardly from said tank through said manifold and communicating with said manifold through a portion 50 extending directly above one of the burners.

4. In a fire pot construction, the combination with a fuel tank, of a combustion chamber, an intake manifold extending transversely of the combustion chamber, a plurality of burners communicating with the manifold and lying at opposite sides thereof adjacent opposite walls of the combustion chamber, and a fuel feed pipe extending upwardly from said tank through said manifold, and means adjacent one of the burners for heating the fuel, and means for conducting the heated fuel to said manifold.

5. In a fire pot construction the combination with a fuel tank, of a substantially rectangular shaped combustion chamber supported above the fuel tank, an intake manifold extending transversely and centrally of the combustion chamber, a plurality of burners communicating with the manifold and lying at opposite sides thereof adjacent opposite walls of the combustion chamber, and a fuel feed pipe extending upwardly from said tank through said manifold, a pipe communicating with said fuel feed and extending within the combustion chamber at one side thereof adjacent one of the burners, and means associated with the last said burner for heating the fuel in said pipe.

6. In a fire pot construction, the combination with a fuel tank, of a combustion chamber supported above the fuel tank, a burner within the combustion chamber adjacent a side wall thereof and provided with means for directing a flame jet away from the wall into the combustion chamber, a pipe for conducting fuel upwardly from said tank, said pipe extending adjacent the aforesaid combustion chamber wall and overlying the burner, and means associated with the burner for directing a flame jet on said pipe.

7. In a fire pot construction the combination with a fuel tank and a combustion chamber, of a pair of opposed burners within the combustion chamber, an intake manifold lying between the said burners, said manifold being divided at one end to form a connection with each of the burners, and a conduit for supplying fuel to the manifold, said conduit extending upwardly from the tank and through the manifold adjacent to its point of division and having a portion directly overlying one of the burners, the said last mentioned burner having fuel discharge openings directed upwardly towards the overlying portion of the conduit.

8. In a fire pot construction, the combination with a fuel tank and combustion chamber, of standards extending upwardly from said tank for supporting said combustion chamber, an intake manifold extending transversely and substantially centrally of said combustion chamber, a pair of burners lying parallel with and on opposite sides of and in the horizontal plane of the said manifold, each of said burners being provided with a fuel discharge opening for directing fuel inwardly of the combustion chamber, and means for supplying fuel to said manifold.

9. In a fire pot construction, the combination with a fuel tank and combustion chamber, of standards extending upwardly from said tank for supporting said combustion chamber, an intake manifold extending transversely and substantially centrally of said combustion chamber, a pair of burners lying parallel with and on opposite sides of

and in the horizontal plane of the said manifold, each of said burners being provided with a fuel discharge opening for directing fuel inwardly of the combustion chamber, 5 and means for supplying fuel to said manifold, said means comprising a conduit extending upwardly from the tank and through the manifold at the point of its connection with the said burners, said conduit having a portion directly overlying one of 10 said burners, said last named burner having a fuel discharge opening directed upwardly towards said overlying portion of the conduit.

15 10. In a fire pot construction, the combination with a fuel tank and combustion chamber, of standards extending upwardly from said tank for supporting said combustion chamber, an intake manifold extending 20 transversely and substantially centrally of said combustion chamber, a pair of burners lying parallel with and on opposite sides of and in the horizontal plane of the said manifold, each of said burners being provided 25 with a fuel discharge opening for directing fuel inwardly of the combustion chamber, and means for supplying fuel to said manifold, said means comprising a conduit extending upwardly from the tank and having 30 a portion overlying one of said burners, said last named burner having a fuel discharge

opening directed upwardly toward said overlying portion of the conduit.

11. In a fire pot construction, a combustion chamber, burners within said chamber, 35 an intake manifold in proximity to said burners, a flame plate associated with the manifold and arranged to direct the flame from the burners inwardly of the combustion chamber, a source of fuel, and means 40 for supplying the manifold with the fuel.

12. In a fire pot construction, the combination with a fuel tank of a combustion chamber supported above the fuel tank, a pair of opposed burners within the combustion 45 chamber, an intake manifold lying between and in the plane of the said burners, a flame plate overlying the manifold and arranged to direct the flame from the burners inwardly of the combustion chamber, and a conduit 50 extending upwardly from the fuel tank for supplying fuel to the manifold, said conduit having a portion directly overlying one of the burners, the said burner being provided with discharge openings directed upwardly towards the overlying portion of the conduit. 55

In testimony whereof we affix our signatures.

OTTO J. GROEHN.
WILLIAM BLASKEWITZ.
